DEVICE FOR SETTING UP COLOR COMBINATIONS

Application filed September 9, 1929. Serial No. 391,428.

This invention relates to a device for setting up color combinations, the object being to provide an improved structure wherein a specific color combination may be secured by 5 manually adjusting certain parts and automatic color combinations are produced by bodily shifting the first combination from place to place.

Another object of the invention is to provide 10 color combinations for presenting different arrangements of stripes or bands to be used in knit goods or other goods, the structure of the device being such that wide or narrow bands of different colors may be 15 quickly produced to secure the desired effect on the eye, and when secured, may be locked against derangement, so that the members making up the combination may be bodily shifted to indicate other combinations.

20 A further object, more specifically, is to provide an apparatus with a casing enclosing a plurality of rotatable disks, each having colored sections on the periphery adapted to be moved past a window so that by rotating 25 the disk different colored combinations may be secured, and by locking the disk against individual rotation groups of combinations may be secured by rotating all of the disks simultaneously.

30 In the accompanying drawings,—

Figure 1 is a perspective view of an embodiment of the invention, the lid or cover plate being partly open;

Figure 2 is an enlarged perspective view 35 of one of the color disks shown in Figure 1;

Figure 3 is a sectional view through Figure 1 approximately on the line 3—3, the same being on an enlarged scale.

Referring to the accompanying drawings 40 by numerals, 1 indicates a casing which may be wood, metal or other suitable material, and mounted on one face of this casing is a covering plate 2 having an opening 3 acting as a window through which the various disks 45 or plates 4 may be seen, or rather, through which part of the disks may be seen.

As shown in Figure 1, a cover 5 is hingedly connected to the casing 1, so that the window may be closed against the entrance of dust 50 and the like. The disks 4 may be made from

metal, wood or other material and may be made any desired thickness, as for instance, one-quarter of an inch, one-eighth of an inch or one-sixteenth of an inch thick. The diameter of the disks 4 may be varied, but in 55 every instance the periphery is provided with a number of cuts or notches 6, said cuts or notches 6 being spaced apart for about the same width as the window 3. The section 7 formed between each pair of the notches 6 is provided with a coating 8 of coloring matter. As shown in Fig. 2, the disks 4 are provided with twenty-four sections 7, and a coating 8 is provided on the periphery of each section, each coating being of a different 60 color or shade from the remaining coatings, or in other words, as there are shown twenty-four sections there will be twenty-four different colors used. The same colors are used 65 on all of the disks 4, that is, the same twenty-four colors or shades are used on each disk, so that, if desired, they could be arranged 70 so that all the coatings 8 shown through window 3 will have the same color, as for instance, red. The device is seldom if ever 75 used in this manner, but on the contrary, is used to present different color combinations, as for instance, different stripes to be used in preparing knit goods, as, for example, a knit sweater. In forming knit sweaters it is cus- 80 tomary to provide ornamental bands at different places, and these bands quite often vary in width and in color. To secure a desired combination of bands and colors is very 85 important but rather difficult of accomplishment without a great deal of work. By using the device embodying the invention the different disks 4 may be rotated quickly and 90 easily, whereby different stripes are presented. The portion seen through window 90 3 is intended to represent a similar portion taken vertically from a sweater or other piece of knit goods. The device could also be used in designing woven goods. If a design was to be made for a sweater and the 95 body of the sweater was to be white, all the disks 4 would be rotated until nothing but white would be seen through the window 3. After this was done the designer would move some of the disks until other colors appeared. 100

For instance as shown in Fig. 1, the portions 9 and 10 indicate other colors from the main base or body 11. The same is true of the sections or portions 12 and 13. In case these stripes are not wide enough, additional disks 5 adjacent these stripes may be rotated until the desired colors appear, so that these stripes may be widened, and if the combination is not that desired, the disks may be all 10 rotated back to their former position, or may be rotated so that the stripes will become wider or narrower, or certain disks may be rotated which will have the effect of shifting the stripes upwardly or downwardly. After 15 a desired color combination has been secured in this manner by manually shifting the disks 4, knob 14 is rotated for clamping the disks 4 tightly together. It will be noted from Fig. 3 that the knob 14 is pinned or 20 otherwise rigidly secured to the shaft 15, and this shaft extends through the sleeve 16 to which it is secured by pin 17. The inner end of shaft 15 is provided with an inner section 18 adapted to screw into the internally-threaded portion 19 of the tube 20. Compressing washer 21 surrounds tube 20 25 and the sleeve 16 presses against this washer when the knob 14 is turned in the proper direction. The pressure against washer 21 crowds the disk 4 over against the washer 22 which in turn presses against the gear wheel 23, and this gear wheel is positioned so that 30 its hub will press against the end plate 24. A pinion 25 continually meshes with gear 35 wheel 23, and shaft 26 is rigidly secured to pinion 25 and to the hand wheel or knob 27. After the knob or wheel 14 has clamped all 40 of the disks 4 together, hand wheel 27 may be rotated, and in this way power will be transmitted through pinion 26, gear wheel 23 and associated parts to the disks 4 which 45 are held together as one unit. As the disks 4 rotate as a unit successive combinations or colors pass the window 3 and quite often the automatically secured combinations are more 50 desirable than the ones secured by the designer in his shifting of the disks 4 manually. By reason of the fact that there are twenty-four sections 7, there will be twenty- 55 four combinations. It will, therefore, be evident that if there are more sections a greater number of combinations will be secured, or if there are less sections a lesser number of 60 combinations will be secured. In any event the designer will have his original design which he has secured in less time than it would have been done by hand sketching, and in addition, he has a large number of other combinations which may be very desirable. 65 After one or more combinations have been taken off or sketched on paper the knob 14 may be rotated in a reverse direction so as to loosen the disks 4, and then the designer may again individually manipulate any disks to 70 secure a new combination, and when the new

combination is secured the disks may be clamped together and the automatic combinations observed by rotating wheel 27. Heretofore in providing designs for sweatshirts or other knit goods, or even for woven 75 goods, it was necessary for the designer to sketch out, usually in full size, the stripes to be used, and quite often it was necessary to make a large number of sketches with different combinations of widths and colors before 80 a desired combination was secured. This required time and was very expensive, as most of the work was of no value. In the present instance mechanical means have been provided, whereby an artist may quickly secure a desired combination of colors and a 85 desired combination of stripes of different widths and positioned in different places in respect to each other.

What we claim is:—

1. A device for setting up color combinations, including a supporting shaft, a plurality of disks independently rotatably mounted on said shaft, means covering said disk except at one point, each of said disks 90 having a plurality of spaces on the periphery and each space being differently colored, whereby a person operating through said window may rotate each disk independently so as to secure a desired color combination, 95 means for locking all of said disks together, and means for manually rotating all of said disks simultaneously.

2. A device of the character described, including a plurality of independent rotatable 100 disks positioned with their axes coincident, each disk having a plurality of differently colored sections on the periphery, means for clamping the disks together so that they may 105 rotate simultaneously, and a closure for said disks formed with a window having a width approximately the length of one of said color sections, said window being formed of such length as to extend across all of said disks parallel to the axes of the disks, whereby one 110 section of each disk will be seen.

3. A device of the character described, including a plurality of independent, movable members, each member being provided with a plurality of differently colored sections, 115 means for clamping said members together so that they may be moved as a unit, and means covering said members, said means being provided with a window having a width substantially equal to the length of one of 120 said sections, said window being of a length sufficient to extend across all of said movable members in a direction parallel to their axes.

4. A device for setting up color combinations, comprising a plurality of independent 125 disks, each disk having a plurality of differently colored sections, means for rotatably supporting the disks on a shaft so that certain sections may be positioned in alignment to 130 secure a desired color combination of stripes,

means for clamping the disks together so that they will rotate as a unit, and means covering said disks, said means having a window extending transversely of the disks, so that one 5 row of colored sections will be visible and thereby one color combination will be visible, the rotation of said disks as a unit causing new rows of color sections to be brought before the window according to the amount of 10 rotation of the disks.

5. A device for setting up color combinations to be reproduced in sweaters and other garments where stripes of different widths and locations are necessary, comprising a plurality 15 of independent rotatable disks, each disk being divided into a plurality of sections, and each section having the peripheral surface colored with a different color, means covering all of said disks, said means being formed with a window extending parallel to 20 the axis of the disks and of a width substantially equal to one of said sections, whereby a section on each disk will be seen, and manually-actuated means for rotating all of said 25 disks as a unit.

6. A device of the character described, including a plurality of disks, each disk having a radial slot extending from the periphery inwardly to provide independent peripheral 30 sections, a coating of colored matter on each section, said coatings being of different colors, a single axle for supporting all of said disks, hand-operated threaded means for clamping said disks together so that they will 35 act as a unit, and a manually-actuated train of gears for rotating said units.

7. A device of the character described, including a plurality of independent members independently movable with respect to each 40 other, each of said members having a series of colored sections whereby when said members are moved until a selected section from each member forms a row, a specific color combination will be produced, means for 45 mounting said member so that when a row having a desired color combination is formed the remaining sections will be brought into rows having other color combinations, and means for clamping said members together so 50 that said members will act as a unit.

8. A device for designing striped effects and patterns for reproduction on fabrics, comprising a plurality of disks of the same size grouped together, each of said disks having 55 a plurality of differently colored sections on the periphery, the colored sections of the respective disks being identical, whereby when certain color sections are in alignment striped effects will be produced, there being 60 as many striped effects as there are sections on a disk.

9. A device for designing striped effects and patterns for reproduction on fabrics, comprising a plurality of disks of the same 65 size grouped together, each of said disks hav-

ing a plurality of independent sections, each section being of a different color, there being the same number of sections on each disk and the respective sections on each disk being colored identically, whereby when said disks are positioned for certain sections to be aligned for presenting a given color combination, the remaining sections will present other color combinations, and means for clamping all of said disks together so that 70 the disks may be rotated for ready inspection of all of the color combinations.

10. A device of the character described including a plurality of independent members independently movable with respect to each other, each of said members having a plurality of color sections of equal length whereby when said members are independently moved until a selected section from each member forms a row, a specific color combination will be produced, while the remaining sections of said members will present a plurality of rows having other combinations, means for clamping said members together so that said members will act as a unit, means forming a window positioned to expose one of said rows at a time, and means for moving said members past said window whereby said rows of color combinations may be observed as they pass 85 said window.
